US00D576057S

(12) **United States Design Patent**
Hebert et al.

(10) **Patent No.:** US D576,057 S
(45) **Date of Patent:** ** Sep. 2, 2008

(54) **BIOMETRIC IDENTIFICATION DEVICE**

(75) Inventors: **Raphael V. Hebert**, Santa Cruz, CA (US); **Tem W. Kuechle**, Santa Cruz, CA (US); **David P. Moriconi**, Ben Lomond, CA (US)

(73) Assignee: **Privaris, Inc.**, Charlottesville, VA (US)

(**) Term: **14 Years**

(21) Appl. No.: **29/281,436**

(22) Filed: **Jun. 22, 2007**

(51) **LOC (8) Cl.** **10-04**

(52) **U.S. Cl.** **D10/46**

(58) **Field of Classification Search** D10/46; D13/162–162.1; D14/383–384; 235/380; 380/23–24, 247; 382/124–127, 115–116, 382/312–314, 188, 118; 356/71; 340/825.34, 340/5.81, 5.8, 5.82, 5.83, 5.84, 5.85; 713/202, 713/182, 183, 184, 185, 186; 705/39, 64, 705/72, 76; 902/40; 455/410; 456/411

(57) **CLAIM**

The ornamental design for a biometric identification device, as shown and described.

DESCRIPTION

FIG. 1 is a top view of a biometric identification device;

FIG. 2 is a left side view;

FIG. 3 is a bottom view;

FIG. 4 is a right side view;

FIG. 5 is a front view;

FIG. 6 is a rear view;

FIG. 7 is a top perspective view; and,

FIG. 8 is a bottom perspective view.

1 Claim, 8 Drawing Sheets

FIG. 1

FIG.2

FIG. 3

FIG.4

FIG. 5

FIG. 6

FIG. 7

FIG. 8
